UNITED STATES PATENT OFFICE.

JOHN M. RHODES, OF CHICAGO, ILLINOIS, ASSIGNOR TO CHICAGO METALLIC PACKING CO., OF CHICAGO, ILLINOIS, A CORPORATION OF ILLINOIS.

PACKING.

Application filed June 1, 1920. Serial No. 385,492.

My invention belongs to that general class of devices known as packing, and relates more particularly to a packing applicable for preventing the leakage of fluids of all kinds, particularly around moving parts. The invention has among its objects the production of a packing of the kind described that is simple, convenient, durable, efficient, reliable, inexpensive and satisfactory for use wherever found applicable. It has among its further objects the production of a packing that is not only extremely efficient in preventing the leakage of fluids or the like, but which packing is extremely durable and of long life. It also has as an object the production of a packing which will perform its function with a minimum of friction, whereby the efficiency of the machine will not be affected by its use. Many other objects and advantages of the construction herein shown and described will be obvious to those skilled in the art from the disclosure herein given.

To this end my invention consists in the novel construction, arrangement and combination of parts herein shown and described and more particularly pointed out in the claims.

In the drawings, wherein like reference characters indicate like or corresponding parts,

Fig. 1 is a view in elevation of a piece of my improved packing with a portion broken away;

Fig. 2 is a sectional view taken substantially on line 2—2 of Fig. 1;

Fig. 3 is a sectional view taken substantially on line 3—3 of Fig. 4 illustrating a slightly modified form of the packing;

Fig. 4 is a side elevation of another form with portions broken away of the same;

Fig. 5 is a sectional view of a modification of the same;

Fig. 6 is a sectional view illustrating the form shown in Fig. 3 with the metal turned side out;

Figs. 7, 8, 9, 10 and 11 are similar sectional views which illustrate other modified constructions.

Fig. 12 is a view in elevation showing a strip of packing folded up with the ends

brought together to produce a packing ring; and

Fig. 13 is a view in elevation of a complete ring without any breaks.

Referring to the drawings, 1 represents a metallic body part which, in the preferred construction, is made up of a plurality of pieces of a suitable metal of the desired size and shape, a suitable lubricant being preferably provided therewith. It may be mentioned that I preferably use a comparatively soft metal such as lead or the like, or some alloy, and I prefer to form the same into strips, ribbons or wire, and coat them with a lubricant which will also serve as a liquid or fluid repellent. I have found graphite very satisfactory for the purpose. I also generally use graphite mixed with oil, the oil serving as a binder for the graphite as well as a lubricant and repellent. By building up the body part 1 of a plurality of plies or strips, the same is more or less flexible and pliable. Referring particularly to Figs. 1 and 2, the body 1 is formed with the face 2 arranged to bear against the part to be packed, as for example a piston or plunger rod, a rotating shaft or the like. The opposite side of the same may be formed as shown at 3, or in a preferred manner, which may depend upon the sizes and uses to which the packing is to be put. In making up the packing there is formed therewith a back, preferably of a yielding or elastic material which is substantially a packing in itself, that is to say, I prefer to use a material which will tend to stop the leakage of fluids or the like. I have found rubber very satisfactory for the purpose. The particular kind of rubber, however, that is to say the composition thereof, may vary depending upon the use to which the packing is to be put, and in some cases it may be preferred to use a fiber or fabric backing, for example in a use where the rubber would be affected by the material which may leak. In Figs. 1 and 2 I have shown the backing in a plurality of parts 4—4, the inner face of which is formed to substantially conform to the shape of part 1, it being understood, as previously mentioned, that the parts may vary in shape depending upon the preference of

the user, and the use to which the packing is to be put. In making up the same I preferably secure the metallic body 1 and the backing 4—4 together and form a unitary structure by means of a cover or retainer 5 of suitable material applied thereto in any desired manner. I have illustrated a woven wire covering 5, and in this case where wire is used, I prefer to use a wire of comparatively soft metal, for example copper, which will not cut or scratch a moving part and does not affect the pliability of the packing. In some cases, however, the same may be covered with a linen, cotton or like fabric or covering of fibrous or other material. One of the advantages of using a woven wire covering is that it does not absorb moisture and the lubricant, for example the graphite, may work through the fabric and lubricate the moving part. Eventually, however, the fabric over the face 2 may be worn away. This does not affect the use as it is primarily intended for a temporary cover to retain the parts together during the shipping and applying. However, the portions extending over parts 4 tend to some extent to hold the several parts together when the packing is in a stuffing box.

The construction shown in Fig. 3 is substantially similar to that described, except that the body part 6 is provided with a covering 8 entirely confining the same, and then the part 6 and cover and the elastic backing 7 are enclosed in another covering 9. In some cases the covering 9 might be omitted, and moulded rubber or like rings employed in connection with the metallic body part. Obviously the meeting faces of 6 and 7 may be as preferred.

The style of packing shown in Fig. 5 is substantially similar to those described, body 11 being provided with the backing 12 of rubber or the like, and the same enclosed with a covering 13, 14 being the bearing face of the packing. With the particular type shown here the elastic or yielding backing 12 is formed in one piece instead of two, as shown in Fig. 2. Fig. 6 is substantially similar to Fig. 2 except that the strip or packing is flexed in the opposite way so as to bring the face 19 at the outside; in other respects the body 15 is provided with the elastic or resilient parts 16 and 17 and covering as at 18.

Referring to Fig. 7, 21—21 represents a metallic body which is made in more than one part, the elastic part 22 being constructed as desired. The parts are retained assembled by means of covering 23 of suitable material. Figs. 8, 9, 10 and 11 illustrate other modified forms. In Fig. 8, 24 represents the metallic body, 25 the elastic backing, 26 the covering. In Fig. 9, 27 represents the metallic body having an apex 28, 29 the backing, and 30 the covering or re-

tainer. In Fig. 10, 31 represents the body, 32 the elastic backing which is extended as at 33, the same being enclosed as in 34. In Fig. 11, 36 represents the metallic body, 35 the elastic backing, and 37 the cover.

In using the packing, which may be produced in various lengths, the same is ordinarily cut the desired length and applied to the desired point, it being understood that the same may be made of strips of any desired size, shape and length. It may be turned or flexed so as to bring the desired face out as indicated. In Fig. 12 I have illustrated a ring 38 constructed by flexing a strip of the desired length and bringing the two ends together as indicated at 39. In this connection it may be mentioned that the ends may be cut off straight so that they abut, or cut at an angle or in any equivalent manner so that they overlap. In Fig. 13 I have shown how the packing may be formed in a complete ring 40 without a break, but in this case it is necessary to make the same to certain sizes, and when so constructed, it necessitates keeping a supply of various sizes on hand. By making the packing in strips of the desired lengths and size, parts may be cut off and rings can be made of any desired size and shape, depending upon the particular application intended.

In using the packing, the same is applied in the stuffing box or the equivalent, and in the case of a moving part to be packed, the metallic body is brought into contact with the moving part. The packing used should substantially fit the box, but the same may be tightened up from time to time to take up for wear in the usual manner by adjusting the gland or the equivalent. The packing is substantially durable, however, and frequent take-ups in the stuffing box owing to wear are generally not necessary. The elastic yielding or resilient backing 4—4 or other types as the case may be, tends to always maintain the metallic body part 1 in contact with the moving parts at all times, affording a tight, leak-proof joint. The packing being substantially flexible, pliable and resilient, contacts at all points, consequently, for example, if there is a flat spot on a rod to be packed, a tight joint may be had immediately upon packing. This is not the case where the packing is not pliable or flexible, as in the case of a rigid or non-flexible metal face the leak will continue until the packing has worn down to make a tight fit. While generally it is preferred to make the meeting faces of the metallic and elastic bodies or parts substantially of the contour or design shown in Fig. 2, I do not wish to be understood as inferring that the design cannot be modified for various sizes and uses. The backing itself is, however, a packing,

and tends to prevent leakage through the box around the body 1. One or more rings or packing elements may be employed, depending upon the needs, and the same in this instance seal against leakage between each other.

It will be particularly noted with the packing herein described, where the same is made as set forth, that the same is extremely pliable as well as flexible, so that it may be fitted and forced into a tight fit to provide a tight joint. It readily conforms to the part to be packed, as for example, it is substantially immaterial if used for packing around a reciprocating rod whether the rod be cylindrical, hexagonal or irregular in cross sectional shape, as the packing will conform thereto. Owing to its pliability, it is readily forced into a tight fit by the elastic backing, and always maintained in position.

Having thus described my invention, it is obvious that various immaterial modifications may be made in the same without departing from the spirit of my invention; hence I do not wish to be understood as limiting myself to the exact form, arrange-

ment, construction and combination of parts herein shown and described, or uses mentioned.

What I claim as new and desire to secure by Letters Patent is:—

1. A packing comprising a backing consisting of a flexible elastic element, and a facing consisting of a flexible non-elastic element, the same being surrounded by a braiding of copper wire, whereby a flexible yielding surface is presented to the moving element.

2. A packing consisting of a metallic body part provided with a wear face at one side, the opposite side being beveled from a point intermediate the edges to the edges adjacent the wear face side, a strip of rubber arranged on each beveled face, with the inner edges of the strips substantially meeting, said strips of a size to provide a back face substantially parallel and equal in width to the wear face, and means for enveloping and securing parts together in assembled relation.

In testimony whereof, I have hereunto signed my name.

JOHN M. RHODES.
